UNITED STATES PATENT OFFICE.

HERMAN E. SCHULTZ, JR., OF ST. LOUIS, MISSOURI, ASSIGNOR TO ZITTLSEN MANUFACTURING COMPANY, OF ST. LOUIS, MISSOURI, A CORPORATION.

UMBRELLA.

1,175,476.

Specification of Letters Patent. Patented Mar. 14, 1916.

Application filed September 4, 1915. Serial No. 48,961.

To all whom it may concern:

Be it known that I, HERMAN E. SCHULTZ, Jr., a citizen of the United States of America, residing in the city of St. Louis and 5 State of Missouri, have invented a certain new and useful Improvement in Umbrellas, of which the following is a full, clear, and exact description, reference being had to the accompanying drawing, forming a part of 10 this specification.

This invention relates to improvements in umbrellas, one of the objects to produce a strong, simple and positive locking means for securing an umbrella in its open position. The novel combination of elements is particularly adapted to form part of a large 15 wagon umbrella having an angular socket member which receives both the central stem of the umbrella and the bracket whereby the 20 umbrella is supported. I preferably simplify the locking means by interlocking the central stem with the supporting bracket, and these parts are preferably retained in interlocking engagement through the 25 medium of the means for securing the umbrella to the supporting bracket. This simple means for locking an umbrella in its open position, adds very little to the cost of the umbrella, and owing to its strength, the 30 locking device is well adapted to withstand the severe shocks to which a wagon umbrella is subjected.

Figure I. is a side elevation, partly in section, showing the central portion of an 35 umbrella frame and the means for locking the umbrella in its open position. Fig. II. is a section taken on line II-II, Fig. I. Fig. III. is a section on line III-III, Fig. I. Fig. IV. is a detail view of the lower portion 40 of the central stem of the umbrella. Fig. V. is a detail view showing a portion of the angular socket member and a portion of the supporting arm.

1 designates ribs pivoted to an upper 45 notch-ring 2, the latter being fixed to a central stem or staff 3. An angular socket member A has a vertical arm 5 adapted to receive the lower end of the central stem 3, and a horizontal arm 6 which is slidably fitted to 50 the tubular arm 7 of a supporting bracket. All of the elements of the umbrella are supported by the tubular bracket arm 7. The lower notch-ring 8 is rigidly secured to the vertical arm 5 of the socket member A, and

the stretchers 9 are pivoted to said notch-ring. The central stem 3 is slidably fitted to the vertical arm 5 of the socket member, and when the umbrella structure occupies its open position, the stem occupies the position shown in Fig. I. In closing the umbrella, 60 the stem 3 is withdrawn from the socket member A.

10 designates a yieldable latch member, in the form of a spring, secured to the central stem 3 and adapted to extend through an 65 opening 11 in the socket member A, so as to yieldingly secure the umbrella structure in its open position.

The umbrella frame, including the ribs 1, stretchers 9 and central stem 3, is secured to 70 the angular socket member A, the latter being detachably secured to the tubular bracket arm 7. The socket member A is slidably mounted on arm 7 and provided with notches 12 adapted to receive a pin 75 13 which projects from arm 7. A threaded sleeve 14, rotatably fitted to the bracket arm 7, is screwed onto a threaded end of the angular socket member.

It will be noted that the socket member 80 A is interlocked with the bracket arm 7 through the medium of pin 13, and that the extended ends of said pin are held in the notches 12 by means of screw threaded sleeve 14. The sleeve has a shoulder 15 which engages the pin 13 when the socket member is 85 locked onto the bracket arm 7.

The lower end portion of the central stem 3 is preferably pressed to form a recess 16 and a lug 17, and when the umbrella is open, 90 an end portion of the tubular bracket arm 7 lies in the recess, and the lug 17 lies in said bracket arm. The umbrella structure is thus securely locked in its open position, the central stem 3 being securely interlocked 95 with the bracket arm 7 so that the stem cannot be accidentally withdrawn from the socket member. The threaded sleeve 14 retains the central stem in interlocking engagement with the bracket arm 7.

In opening the umbrella the central stem is forced into the socket member and automatically latched by the yieldable latch device 10; the latter being an auxiliary latch which does not possess sufficient strength to 100 withstand the severe shocks to which the umbrella is frequently subjected in service. After the umbrella has been secured by the

latch device 10, the socket member A is moved on the bracket arm 7 to interlock said arm with the central stem 3, thereby positively securing said stem in the socket member. Thereafter, the threaded sleeve 14 is tightened to secure the umbrella to the bracket arm 7, and to retain said bracket arm in interlocking engagement with the central stem.

10 I claim:—

1. An umbrella having a central stem, an angular socket member adapted to receive said central stem, ribs and stretchers associated with said parts, a tubular bracket arm constituting a support for said parts, said angular socket member being slidably fitted to said tubular bracket arm and the latter being at an angle to said central stem, the said central stem being recessed to receive an end portion of said tubular bracket arm when the umbrella structure occupies

its open position, and means for securing said angular socket member to said tubular arm so as to retain the end portion of said tubular arm in said recess, thereby positively locking the umbrella structure in its open position. 25

2. An umbrella having a central stem, an angular socket member adapted to receive said central stem, ribs and stretchers associated with said parts, a tubular arm to which said angular socket member is slidably fitted, said tubular arm being at an angle to said central stem, the lower portion of said central stem being provided with a lug adapted to lie within an end portion of said tubular arm when the umbrella structure occupies its open position, and means for securing said angular socket member to said tubular arm so as to retain said lug in 35 said tubular arm. 40
